THERAPEUTIC APPARATUS

Louis B. Newman, Chicago, Ill.

Application August 29, 1936, Serial No. 98,437

15 Claims. (Cl. 128—401)

This invention relates to therapeutic apparatus, and more particularly to such apparatus as is used for the application of heat or cold for the destruction of pathogenic micro-organisms 5 infecting an internal or external part of the human body, or for other purposes, such for instance, for improving the circulation and aiding the resolution of abscesses and other abnormal conditions, and for improving the distribution 10 and action of medicaments.

It is known that many pathogenic micro-organisms are destroyed by the continuous application of heat thereto at a temperature below the destructive temperature for human tissue, 15 and therapeutic apparatus for dealing with such micro-organisms is well known. Such apparatus generally consists of an applicator in the form of a thin rubber bag of the requisite shape for the particular organ of the body to be treated, and means for circulating water at the proper 20 temperature through the applicator. The applicator is made of thin rubber so that when it is distended or inflated by the hot water it will contact with as large a proportion as possible of the surface of the organ being treated.

One of the great dangers in the use of therapeutic apparatus of the above character is that of breakage of the thin rubber applicator. This 25 always causes discomfort or severe pain to the patient, and frequently severe burns. It is known that the destructive temperatures for the tissue of different parts of the body is not the same, and that the requisite destructive temperature for certain pathogenic micro-organisms 30 is only very little below that which will destroy the affected tissue, and may be even above the temperature which will injure more sensitive tissue adjacent the affected tissue. Also, in order to maintain the affected tissue at the proper 35 elevated temperature there must be a continuous flow of heat through the applicator to the tissue, which means that the temperature on the inside of the applicator must be above that on the outside of the applicator, namely above that of the tissue being treated. When it is considered 40 that the temperature to which the tissue is subjected for the destruction of the pathogenic micro-organisms is only slightly below that which will result in destruction of the tissue itself, and 45 may be above the maximum safe temperature for adjacent tissue, it will be appreciated that rupture of the applicator, with the consequent release of the hot water therefrom, is very likely to cause burning of the tissue. Also, the released hot water will flow into the body beyond 50

the applicator and may seriously burn more sensitive tissue. In addition there is the danger of infection being carried by the released water, as well as the possible injury by the water itself. This danger is aggravated by the fact that for 5 many uses the applicator must be made very thin so that, when it is distended, it will contact the entire internal surface of the organ in which it is placed.

It is an object of this invention to provide a 10 therapeutic apparatus of the above character which is not subject to the dangers above mentioned, as well as others, in the event that the applicator should break. By eliminating the possible injury resulting from breakage of the 15 applicator it is possible to use thinner applicators with safety, or to use higher destructive temperatures without fear that possible breakage of the applicator will cause injurious overheating of the tissue. The above result is accomplished 20 by using heated air instead of water as the fluid for inflating and carrying heat to the applicator. By circulating hot air instead of hot water through the applicator a breakage of the applicator can do no harm because the specific 25 heat of air at the elevated temperature is negligible in comparison with the corresponding heat carried by water at the same temperature. Furthermore, a breakage of the applicator will not result in wetting of the patient and consequent 30 embarrassment to both patient and doctor.

It is a further object of the present invention to provide a simple and reliable means for controlling the pressure in the applicator. This result is accomplished by providing a small hand 35 pump for increasing the amount of air in the closed circulating system which includes the applicator, thereby increasing the pressure and causing distention of the applicator. A hand operated relief valve is provided for permitting 40 controlled escape of the air to reduce the pressure in the applicator for partially or completely collapsing the same. In addition, a safety valve is provided for limiting the pressure. By this arrangement the physician can inflate the applicator to the desired degree without danger of 45 injuring the patient, even in the remote contingency that the applicator should break or tear while it is in position. Having thus properly inflated the applicator, the physician is assured 50 that the pressure in the system cannot possibly go up, regardless of what may happen to the electrical system. At such times the applicator is a part of a closed air system containing a fixed amount of air which is maintained in circula- 55

tion by the fan and is maintained at a proper temperature by the heating means. The attendant can then leave the patient, during treatment, because even if an accident were to happen and 5 the applicator should break, no possible injury can result.

It is a still further object of the present invention to provide an applicator so arranged that it may receive a thermometer which will indicate 10 the temperature at the applicator. The thermometer is located at the very point in the system where the heat treatment is being applied so that the physician knows at all times the exact temperature being applied.

15 It is a still further object of the present invention to provide a new method for increasing the effectiveness of various medicaments now applied to the surfaces of human tissue in the treatment of disease or other pathological conditions. When 20 ointments, drugs, or powders are applied to body surfaces, or into body cavities for their therapeutic or medicinal effects, the action is necessarily slow, and frequently uncertain. I propose to increase the effectiveness and speed of action 25 of the medicaments by applying heat to the body tissue, thereby causing the natural dilation of the pores or other tissue surface, and thus increasing the effectiveness of the medicaments. This is particularly important in the treatment of vaginal afflictions.

30 By my process, the various medicaments used are introduced, as in the past, and then the applicator is inserted in place. The heat and pressure of the applicator results in a spreading 35 of the medicaments over the entire tissue and causes more rapid and effective penetration of the medicaments.

It is a still further object of the present invention to use the apparatus above set forth, for 40 treatment where reduced temperatures are desirable, as well as where elevated temperatures are required. When a reduced temperature is desired, the air within the applicator may be cooled, as, for instance, by circulating a refrigerant in a coil within the closed air circulating 45 system, although it is to be understood that any other of a plurality of well-known methods of cooling the air may be resorted to.

The attainment of the above and other objects 50 of the present invention will be apparent from the following specification taken in conjunction with the following drawing forming a part thereof.

In the drawing:

55 Fig. 1 is a diagrammatic view illustrating one embodiment of the present invention;

Fig. 2 is an enlarged view of that end of the apparatus to which the applicator is attached;

Fig. 3 is a sectional view taken along the line 60 3—3 of Fig. 2; and

Figure 4 is a sectional view, in partial elevation, illustrating another embodiment of the present invention.

Reference may now be had more particularly 65 to Fig. 1. The applicator is indicated at 1 and comprises a thin rubber bag of a proper shape, depending upon the particular body cavity for which the applicator is intended, and an applicator head to which the bag is attached. The 70 bag is of thin rubber so that upon inflation it expands to fill the body cavity in which it is placed and contacts as large a portion of the surface of the cavity as is possible. The applicator bag illustrated at 1' is of a shape particularly 75 adapted for treatment of the female pelvic re-

gion. The applicator head is indicated at 2, the applicator bag being secured to the lower end of the applicator head. A thermometer 3 extends through a suitable opening in the applicator head into the applicator bag, so that the thermometer 5 indicates the actual temperature within the applicator bag. The applicator 1 is provided with an air inlet opening adapted to receive a pipe or tube 4, and an air outlet opening adapted to receive a pipe or tube 5. The tubes 4 and 5 extend to the control apparatus located at a convenient adjacent place and which includes a tempering casing 7 for heating or cooling the air, and a fan housing 8, connected together and to the pipes 4 and 5 so as to constitute a closed air circulating system. Air is moved by the fan 8 through the casing 7, thence through the tube or pipe 4, through the applicator 1, outlet pipe 5 and back to the inlet of the fan. The pressure within this circulating system is determined by the quantity 10 of air in the system. The system is made leak-proof to guard against escape of air and consequent loss of pressure. Means is provided for increasing or decreasing the amount of air in the system so that any desired pressure is obtained. This means comprises a bulb pump 10 connected by a tube 11 to the air circulating system at any desired point, for instance at the casing 7. The bulb pump 10 comprises a rubber bulb and a suitable valve arrangement so that 15 upon compression of the bulb the air therein is forced through the tube 11, whereas upon release of the pressure on the bulb 10, air is drawn into the bulb from the atmosphere through an inlet 12, instead of through the tube 11. The inlet 12 may also be operated manually to permit escape of air from the system. This is the usual type 20 of bulb pump used with the ordinary portable blood pressure determining device. A pressure gauge 14 is provided for determining the pressure 25 in the system.

An electric motor 15 is provided for operating the fan 8, and a coil 16, hereinafter referred to as a tempering coil, is provided for heating or cooling the air in the circulating system. In the 30 case of an apparatus designed for cold treatment, the tempering coil 16 may comprise a coil connected to receive a refrigerant from a refrigerating system. In the case of a heat treating apparatus, the coil 16 comprises an electrical resistance coil. The desired temperature can be 35 changed by operating a knob 17 of an automatic thermostatic control 18. In the case of an electric system the knob 17 adjusts a resistance in the control apparatus 17.

Reference may now be had more particularly 40 to Fig. 2 showing the construction of the applicator head. The applicator head consists of an outer pipe 20 having an enlargement 21 at its lower end for receiving the applicator 1. A bore 22 is formed in the enlargement for receiving the thermometer 3. The thermometer seals in the bore 22 so that there can be no escape 45 of air from the applicator at the point of entrance of the thermometer. The pipe 20 is adapted to be connected with a pipe 24 by means of a universal coupling 25 suitably gasketed at 50 26 to prevent the leakage of air. The pipe 24 has two branches, viz: a branch 28 and a branch 29. The branch 28 is adapted to receive a rubber tube 5 at its outer end and constitutes the air outlet side of the applicator. The branch 29 has a pipe 30 therein which extends through that branch and through the pipe 20 to the applicator. The branch 29 is adapted to receive 55

a rubber tube or pipe 4 which constitutes the air inlet side to the applicator. The applicator is slipped over the head 21 of the pipe 20 and may then be inserted in place for treatment of the patient. Thereafter the physician connects the pipe 29 to the pipe 20 by means of the universal connection 25. This subjects the patient to a minimum amount of discomfort during the insertion of the applicator into position.

10 It is apparent from my above description that I have provided a simple and reliable apparatus for therapeutic treatment. By means of this apparatus the treating temperature can be changed at will and with great rapidity. Also, 15 after the applicator is inserted in place, the physician does not have to maneuver the applicator to eliminate air bubbles, such as must be done with applicators employing water as the heating fluid. Also, in the event that the 20 applicator should rupture while in use, the patient is not subject to the possibility of being burnt, nor to the discomfort, annoyance and embarrassment that results when a water-treating therapeutic device ruptures. Furthermore, 25 in the event of rupture of the applicator bag, a new bag can quickly be inserted in place and treatment continued. With therapeutic devices employing water as the heating fluid, this cannot be done quickly because of the water that has escaped. Not only must the fresh water be heated, which takes time, but the bed linens must be changed, which takes additional time. This means that the entire effect of the heating, 30 up to the time of the rupture of the applicator, may be lost because of the time delay.

Reference may now be had to Fig. 4, wherein I show, diagrammatically, an applicator of the type illustrated in Fig. 3, but of a simpler construction, in that here the heater is placed directly in the applicator, and the air is not circulated through the applicator. The applicator is indicated at 1, being mounted at the end of a tubular handle 32, to form a seal-tight fit. The handle 32 is provided with an opening 33 whereby air may be forced into the applicator by means of a bulb pump 10, which is connected to the handle 32 by means of a tube 34. Tempering apparatus 36 is inserted into the applicator, said tempering apparatus being supported by the tubular handle 32 and provided with a sealing tube 38 for preventing the escape of air or other gas from the applicator 1 through the inlet for the tempering device. The tempering device may consist of a cooling coil, when the apparatus is to be used for cooling purposes, or it may consist of an electric heater when the apparatus is to be used for heating purposes. A thermometer 3 is provided for indicating the temperature within the applicator. A baffle 39 55 shields the end of the thermometer from the direct influence of the tempering apparatus. In using the device of Fig. 4, the physician inserts the applicator in place and then inflates it the requisite amount. Thereafter, the temperature 60 within the applicator is raised or lowered, depending upon the type of treatment, by means of the tempering device. If desired, a pressure gauge, such as the gauge 14 of Fig. 1, may be provided for this purpose.

70 While the applicator shown in the drawing is particularly useful for insertion into a body cavity, it is not limited to such use, as it may readily be applied to the exterior surface of the body, wherever heat or cold treatment is desired. 75 Also, the applicator may be made of any shape,

depending upon the particular body surface where it is to be used.

In compliance with the requirements of the patent statutes, I have here shown and described a preferred embodiment of my invention. It is, 5 however, to be understood that the invention is not limited to the precise method here disclosed, nor to the precise method and apparatus here shown and disclosed, it being merely illustrative of the principles of the invention. What I consider new and desire to secure by Letters Patent is:

1. Therapeutic apparatus comprising an air-tight flexible applicator, means for moving a gas through the applicator, and means for changing 15 the pressure of the gas in the applicator.

2. Therapeutic apparatus comprising a gas system including an applicator, means for circulating a gas through the applicator, means for controlling the temperature of the gas in the 20 applicator, and means for varying the pressure of the gas in the applicator.

3. Therapeutic apparatus comprising a distendable applicator, means forming a closed, air-tight circulating air system including said 25 applicator, means for circulating the air in said system, and means for increasing the air pressure in said system to distend the applicator.

4. Therapeutic apparatus comprising a distendable applicator, means forming a closed, air- 30 tight, circulating air system including said applicator, means for circulating the air in said system, means for increasing the amount of air in said system to distend the applicator, and means for regulating the temperature of the air 35 in the applicator.

5. In combination with an inflatable applicator having means forming gas inlet and gas outlet openings, connections between the two openings for establishing a closed gas circulating system 40 including said applicator, means in said system for circulating gas through the applicator, means for regulating the temperature of the gas in the system, and means for forcing gas into the system to increase the pressure and thus distend 45 the applicator.

6. A therapeutic device comprising in combination, an inflatable applicator having means forming gas inlet and gas outlet openings, connecting means between said openings forming a 50 closed air circulating system including said applicator, a fan in said system for circulating air through said applicator, a hand operated air pump receiving air from the atmosphere and having an outlet connected to said system for 55 delivering air to the system to increase the pressure in the system for distending the applicator, means for controlling the temperature of the air in the circulating system comprising an electric heating coil and controlling means for controlling the amount of heat generated by the coil, thermally responsive means located in the applicator for indicating the temperature of the air in the applicator, and a relief valve for relieving 60 the pressure in the applicator. 65

7. Therapeutic apparatus comprising means forming a gaseous fluid system including an applicator having a distendable applicator bag, means for increasing the amount of gas in the entire system for inflating the bag and means for effecting a heating of the body structures adjacent the applicator bag, said heating means being substantially spaced from parts of the applicator which come into contact with parts of the body, and fluid of said system being in said space. 75

8. In combination, a tubular member having a substantially thickened end portion, an inflatable applicator bag having a neck fitting over and embracing the thickened portion, a thermal responsive member extending through the thickened portion and into the bag, with that part of the thermal responsive member which is outside of the bag and outside of the thickened portion being located adjacent the tubular member whereby the tubular member acts as a protective shield for the thermal responsive member, and means connected to the tubular member for forcing fluid therethrough into the bag for inflating the bag.
9. Therapeutic apparatus comprising in combination an air system including an inflatable applicator having an air inlet opening and an air outlet opening, means for moving air through the applicator and increasing the pressure of the air above atmospheric pressure to maintain the applicator inflated, said means including an air fan connected to the air inlet side of the applicator and continuously operable to maintain a continuous movement of air through the applicator from the inlet to the outlet side of the applicator, and means for varying the temperature of the body structures adjacent the applicator by varying the temperature of the air in the applicator.
10. Therapeutic apparatus comprising an air-tight flexible applicator, means for moving a gas through the applicator, means for changing the pressure of the gas in the applicator and means for refrigerating the gas.
11. Therapeutic apparatus comprising a distendable applicator, means forming a closed, air-tight, circulating air system including said applicator, means for circulating the air in said system, means for increasing the quantity of air in the system to increase the air pressure of the air in said system to distend the applicator and means for cooling the air in said system.
12. Therapeutic apparatus comprising in combination an air system including an inflatable applicator having an air inlet opening and an air outlet opening, means for moving air through the applicator and increasing the pressure of the air above atmospheric pressure to maintain the applicator inflated, said means including an air fan connected to the air inlet side of the applicator and continuously operable to maintain a continuous movement of air through the applicator from the inlet to the outlet side of the applicator, and means for cooling the temperature of the body structures adjacent the applicator,
- said last named means comprising means for refrigerating the air.
13. Therapeutic apparatus comprising an air-tight flexible applicator, means for moving a gas through the applicator, and means for changing the pressure of the gas in the applicator, said flexible applicator including a bag through which the gas is moved and said applicator having inlet and outlet openings for movement of gas simultaneously into and out of the bag, said bag being sufficiently thin and flexible to enable it to conform itself to the shape of an adjacent surface of the human body with which it is in contact.
14. Therapeutic apparatus comprising an air-tight flexible applicator including a bag adapted to be inserted into a human body cavity, means for moving a gas through the applicator and maintaining the gas in continuous movement within the applicator, means for changing the pressure of the gas in the applicator bag to inflate the bag into engagement with the inside surface of the body cavity, said bag being sufficiently thin and flexible to enable it to conform itself substantially to the shape of the body cavity when inflated and thus to contact a substantial area of the surface of the body cavity, and means outside of the applicator bag for heating the body tissues adjacent the bag to a temperature substantially above body temperature by varying the temperature of the air in the bag.
15. Therapeutic apparatus for destroying infectious micro-organisms near a cavity in the human body by elevating the temperature of the infected region above the destructive temperature for the infectious micro-organisms but below the temperature at which objectionable destruction of adjacent human tissue takes place, said apparatus comprising an air-tight flexible applicator including a bag adapted to be inserted into a body cavity, means for moving a gas through the applicator and maintaining the gas in continuous movement within the applicator, means for changing the pressure of the gas in the applicator to inflate the applicator bag into engagement with the inside surface of the body cavity, said bag being sufficiently thin, elastic, and flexible to enable it to conform itself substantially to the shape of the body cavity so that when inflated it contacts a substantial area of the body cavity, and means outside of the applicator bag for heating the gas to raise the temperature of body tissues adjacent the bag sufficient to effect destruction of infectious micro-organisms.

LOUIS B. NEWMAN. 55
